UNITED STATES PATENT OFFICE

2,599,878

TUBE AND METHOD OF MAKING THE SAME

Rudolph H. von Liedtke, Chicago, Ill., assignor,
by mesne assignments, to McGraw Electric
Company, a corporation of Delaware

Application September 4, 1945, Serial No. 614,355

1 Claim. (Cl. 92—66)

1

This invention relates to an article such as a tube formed of layers of paper pulp or other fibrous materials which in the case of the tube is formed of wound layers of pulp and also relates to the method of securing successive layers together in a manner to produce the effect of stitching successive layers together.

For the sake of simplicity in describing the invention, the description will be directed to the method of producing a wound paper tube, though it is to be understood that the invention is not limited solely to tubes and their manufacture, but is applicable to other shapes of articles where they are manufactured from a plurality of layers of paper or similar pulp.

In manufacturing tubes formed of wound paper pulp or other fibrous materials, it has been found that sometimes the successive layers of the paper pulp do not adhere to preceding layers as firmly as might be desired and, in addition to this, it frequently happens that during the winding air or water is trapped between the oncoming layer and the partially wound tube thus producing voids in the wall of the tube. These voids and this lack of adherence materially weakens the tube even after the tube is impregnated with a nonabsorbent, binding material. In addition to this, the dielectric strength of the tube is lowered.

This invention is designed to overcome the above noted defects and objects of this invention are to provide a tube and a method of making the same in which the successive layers of the paper pulp are securely attached to preceding layers in such a manner as to produce the effect of stitching successive layers together, the process also immediately affording relief of the air or water trapped in the voids at the time the voids tend to form during the winding of the tube, thus providing a tube which has its layers firmly bound to each other and also producing a tube which is substantially free from voids.

Various embodiments of the machine and various steps in the process of making the impregnated tube are shown in the accompanying drawings in which:

Figure 1 is a transverse sectional view through the machine, such view corresponding to a section on the line 1—1 of Figure 2.

Figure 2 is a side elevation partly in section and partly broken away of a portion of the machine.

Figure 3 is a fragmentary view showing the manner in which the stitching roller or drum operates.

2

Figure 4 is a view showing a further form of stitching drum.

Figure 5 is a view of a fragment of a tube with a temporary sealing coating on the outer surface of the tube.

Figure 6 is a fragmentary view of a portion of the impregnated tube.

Figure 7 is a fragmentary view of a portion of a tube showing a void in the tube.

Figure 8 is a diagrammatic view showing the paper pulp being wound on a mandrel.

Figure 9 is a perspective view of the tube as it comes from the tube forming machine.

Figure 10 is a view of a fragment of the tube, such view being in section and partly broken away.

Figure 11 is a view of the impregnating tank.

Figure 12 is a fragmentary view of a portion of the tube, such view being partly in section showing one stage in process of impregnation.

Figure 13 is a view corresponding to Figure 12 showing a further step in the process of impregnation.

Figure 14 is a view corresponding to Figure 12 showing the finished impregnated tube.

In carrying out the process a conventional type of tube forming machine may be employed in which a tank 1 is provided for the paper pulp 2. This paper pulp is fed to the tank 1 in any suitable manner, not shown, and is maintained at the proper level. A hollow drum or roller 3 is provided and has a perforated peripheral portion surrounded by a screen 4. A partial vacuum is produced within the drum 3 and the paper pulp is sucked up against the drum, the drum being rotated in the direction indicated. This paper pulp passes to an intermediate hollow perforated drum 5 which is surrounded with a layer of felt or suitable material 6 and preferably a higher vacuum is produced in the drum 5. The drum 5 receives the layer of paper pulp from the drum 3 and delivers it to a mandrel 7 on which the tube is wound. The machine is provided with a plurality of mandrels 7 carried in suitable rotatably mounted heads 8 which are slotted as indicated at 9 to receive the reduced trunnions 10 of the mandrels. The heads 8 and the mandrels 7 are adapted to be regularly indexed to bring successive mandrels into operative position and locking means are provided for temporarily locking the heads and the mandrels in their successive positions.

The locking means may take any suitable form. For instance, it may consist of a lever 11 pivotally mounted as indicated at 12 and pro-

vided with a foot or locking means 13 adapted to enter the notches or slots 9 in one of the heads 8. Suitable means are provided at opposite ends of the machine for pressing the lowermost mandrel downwardly towards the drum 5. This means may consist of a pair of rollers 14 at opposite ends of the machine, see Figure 2, which are spring-pressed downwardly in any suitable manner, not shown, in accordance with the usual practice. The heads 8 and the locking means 13 constitute indexing means and thus allow the mandrel carrying heads to be indexed as the tubes are completed. Guard rails 15 extend part-way around the heads and prevent escape of the trunnions 10 from the slots 9 except in one position, for instance, the left-hand position of Figure 1, to allow the removal of a wound tube from a mandrel. The machine may be driven in any suitable manner. For instance, in accordance with the usual practice the drum 5 may be driven by means, not shown, and may thus drive the lower drum 3 and the mandrel 7 on which the tube is being wound. The machine thus described is the conventional type of tube forming machine and the usual accessories are, of course, provided in accordance with the usual practice.

This invention contemplates the stitching or securing of successive layers to preceding layers during the formation of the wound paper pulp tube. The stitching is accomplished by means of a stitching roller 16 which is journaled at opposite ends in the bell crank levers 17 pivotally mounted as indicated at 18 upon floating pivoted heads 19 loosely carried by the central shaft 20, which central shaft 20 is rigid with the end heads 8. The upper portions of the bell crank levers 17 are joined by means of a transverse bar 21. This transverse bar constitutes means whereby pressure may be applied between the stitching roller 16 and the tube. The operator, in the instance chosen for illustration, presses against the transverse bar 21 and thus forces the stitching drum or roller 16 against the tube while it is being wound. Any other suitable means may be provided for accomplishing the same result, the means chosen being merely one of many possible ways of accomplishing the desired result. The stitching roller is provided with a multitude of prongs or pin-like projecting portions 22 which are shown more clearly in Figure 3. It will be seen that as the partially wound tube rotates that the prongs or projections 22 will be forced into the successive layers and will force the succeeding layers into preceding layers thus in effect stitching successive layers together. Only one of the indentations is shown in Figure 3 though it is to be understood that a multitude of indentations or stitch points are provided. If desired, the pressure exerted on the stitching roller 16 may be sufficient to cause the prongs 22 to actually puncture one or more layers.

The stitching roller may take other forms. For example, as shown in Figure 4 the stitching roller 16' may have angular or bent points 22' if desired. It will be seen that by the method hereinabove described the successive layers are firmly united with preceding layers by forcing a portion of one or more layers into or through portions of preceding layers. This is illustrated more clearly in Figure 5 in which the completely wound tube is indicated by the reference character 23 and the stitching points by the reference character 24.

It frequently happens that voids or spaces are formed as indicated at 25 during the winding of the tube. These spaces or voids are produced by entrapped air or water between the oncoming sheet of paper pulp 26, see Figure 8, and the partially formed tube at the point indicated by the reference character 27.

It is to be noted also that wherever any of the stitching points reaches one of the voids that the air or water entrapped in the void is allowed to escape and the formation of voids is very much reduced if not substantially prevented. It is to be noted that the stitching roller is a relatively long roller and is provided with a multitude of spaced points or pins as shown in Figure 2. The pressure exerted between the stitching roller 16 and the tube while it is being wound is distributed over a multitude of points and consequently there is no danger of one point digging into the partially formed tube to an inordinate extent. The amount of penetration is gauged or controlled by the amount of pressure employed.

After a tube has been completely wound pressure on the stitching roller 16 is relieved and the heads 8 and the mandrels 7 are indexed one quarter of a turn in the form shown in Figure 1 to bring a new mandrel into position and to allow the removal of the finished tube. The heads are indexed in the direction shown in Figure 1 and it will be seen that the stitching roller 16 is pushed upwardly during this operation and allows free passage of the completed tube. It drops back into position to engage the tube being formed on the succeeding mandrel and again pressure is applied through the medium of the pressure bar 21 or in any other suitable manner. The tube, after removal from the mandrel, is thoroughly dried and is later impregnated with pitch in the usual manner. It is preferable, however, to follow the method of impregnating the tube set forth in the copending application for Impregnated Article and Method of Impregnation, Serial No. 614,354, filed September 4, 1945, by Rudolph H. Von Liedtke, now Patent 2,478,439.

In following the method set forth in the copending application hereinabove noted, spray means such as indicated by the reference character 28 in Figure 1 is provided for spraying a temporary sealing coating of size 29, see Figure 12, on the outer side of the tube. This spraying takes place during the winding of the last few convolutions of the tube and any suitable sizing material may be employed provided it has the characteristics of sealing the surface of the tube and also of disintegrating or disappearing or becoming ineffective for a certain temperature range of the pitch thus allowing the coating to either disintegrate or disappear at a certain stage in the process of impregnating the tube. A suitable size is silicate of soda which is sprayed on the tube as described. It may be sprayed either on the first few convolutions to thus seal the inner surface of the tube or may be sprayed on the outer convolutions of the tube to seal the outer surface of the tube. The tube with the sealing coating thereon is thoroughly dried and after drying is placed in the impregnating tank 30, see Figure 11. This impregnating tank is supplied with heated pitch through the supply pipe 31 at its lower portion and the pitch is pumped from the upper portion of the tank through the outlet pipe 32 by means of a pump 33 or in any other suitable manner so that heated

5

pitch is circulated through the tank. The tank is provided with a lower steam jacket 34. The upper portion of the tank is connected to a three-way valve 35 which is adapted to connect the tank with a suitable source of vacuum by means of the vacuum pipe 36 or with the outside air or air under pressure by means of the air pipe 37 depending upon the setting of the valve.

When the tubes are positioned within the tank the pitch is caused to circulate and the three-way valve 35 is turned so as to produce a vacuum in the upper portion of the tank. This lowers the temperature of the pitch and prevents destruction of the sealing coating. The air it will be noted which is entrapped within the wall of the tube flows radially inwardly in one direction only away from the sealing coating. After a suitable interval of time the three-way valve is turned to admit air to the upper portion of the tank and to relieve the vacuum. The pitch now flows radially from the uncoated inner side of the tube towards the coated side of the tube and thus uniformly impregnates the wall of the tube. When the vacuum is relieved the temperature of the pitch rises and the sizing coating or sealing coating 29 disappears or is substantially destroyed after a predetermined interval of time and allows the pitch free access to the outer surface of the tube. In this way there is no chance of air being trapped within the wall of the tube which would prevent even and complete penetration of the pitch. The sealing coating is indicated in Figures 5 and 12 and a fragment of the finished tube is indicated in Figures 6 and 14. For the sake of simplicity, it is to be noted that the stitching points have been omitted in Figures 7, 10, 12, 13, and 14.

The stitching of the tube binds successive layers together and relieves the voids. The result of this is that the successive layers of the tube are very firmly bound together not only by the binding action of the pitch which is a waterproof, binding, impregnating agent, but also due to the stitching of the successive layers.

The stitching occurs at a multitude of closely spaced points, a few only of which have been shown in Figures 5 and 6.

It will be seen that a novel method of binding successive layers of a paper pulp tube together has been provided by this invention by means of a stitching process which actually forces portions of succeeding layers into portions of preceding layers at a multitude of closely spaced points and

6

which thus causes a very firm interlocking or unification of the layers of paper pulp composing the tube. It will be seen further that the method does not slow up the normal operation of winding or forming these paper pulp tubes but may be followed with the utmost ease and may be adapted to ordinary types of tube forming machines with only minor alterations.

The expression "paper pulp" appearing in the specification and claims is not intended as a limiting expression as it is obvious that this invention is applicable to any type of article and to the process of making such article where the article is made from fibrous pulp or fibrous material whether it is strictly paper pulp or not.

Although this invention has been described in considerable detail, it is to be understood that such description is intended as illustrative rather than limiting, as the invention may be variously embodied and is to be interpreted as claimed.

I claim:

An article of manufacture comprising a tube formed of a plurality of layers of paper pulp pressed into firm contact with each other throughout their extent wound one upon another, said tube having succeeding layers pressed into the body of preceding layers at a multitude of spaced points to stitch the layers together, the points at which successive layers are stitched to the body of preceding layers being spaced both circumferentially and radially from each other, said tube being characterized by the fact that it is a compacted structure throughout its extent.

RUDOLPH H. VON LIEDTKE.
